WALL-HUNG DRINKING FOUNTAIN

Halsey W. Taylor, 205 Golf Drive NE, Warren, Ohio

Filed Aug. 18, 1959, Ser. No. 57,211

Term of patent 14 years

(Cl. D67—4)

Fig. 1

The dominant features of my design reside in the portions shown in full lines in the drawing.

I claim:

The ornamental design for a wall-hung drinking fountain, substantially as shown and described.
